UNITED STATES PATENT OFFICE

ISIDOR TARLOW, OF BROCKTON, MASSACHUSETTS

SPORT-SHOE HEEL-ATTACHING APPARATUS

Application filed January 3, 1929. Serial No. 330,021.

This invention relates to improvements in apparatus for attaching shoe heels of the kind used for sport shoes wherein the tread face is provided with projecting spikes.

- 5   Heel nailing machines supplied by manufacturers of shoe machinery are so designed that the heel attaching nails can be driven accurately only if the heel has a smooth tread, that is, a top lift without spikes or
 10 other non-slip projections. It is essential, in the heel attaching operation, that the heel to be nailed is clamped securely between the die block and the jack of the nailing machine. The die blocks of nailing machines offered
 15 to the trade, such as the "lightning nailer" generally in use, have a flush under face for engaging the tread face of the heel. If a sport shoe heel is to be attached the spikes engage the under face of the die block and
 20 hold the heel away from the die block which is fatal to an accurate driving of the heel attaching nails. This condition has resulted in many cripples due to bent heel nails and manufacturers of sport shoes provided with
 25 spiked heels have had to resort to the slower and more expensive attachment of the heels by hand nailing.

The object of the present invention is to improve the construction of apparatus for attaching heels, and more particularly to improve the die block of heel nailing machines, in a manner to insure proper attachment of spiked heels to the shoe when machine nailed.

To the accomplishment of this object, the invention comprises a heel nailing machine having the features and combinations of parts hereinafter described and then particularly pointed out in the appended claims.

The features and scope of the invention 40 will best be understood from a description of the preferred embodiment thereof illustrated in the accompanying drawings, in which:

Figure 1 is a view, in front elevation, of a 45 portion of a representative type of heel nailing machine showing the relation of the nailing head, die block, sport shoe and jack after the heel nails have been driven, the shoe and the central portion of the die block both being shown in section; Fig. 2 is an under face

view of the improved die block; Fig. 3 is a view, greatly enlarged, of the central portion of the under face of the improved die block; Fig. 4 shows, in perspective, one type of spiked heel that may successfully be nailed 55 by following the teaching of the present invention; and Fig. 5 shows, in perspective, the sport shoe heel of Fig. 4 attached to a shoe.

In the embodiment of the invention illustrated in the drawing, it being fully understood that the usefulness of the invention is not limited to attaching the particular sport shoe heel shown which is the subject-matter of a co-pending application for patent Serial 60 No. 330,020 filed January 3, 1929, a sufficient portion of a shoe nailing machine is shown in Fig. 1 to enable the application of the invention thereto to be understood, namely the nailing head 10, the die block 12, and the jack 14 having a shoe 16 thereon. The shoe, after having been bottomed, is placed on the jack as usual, and the spiked heel having been positioned under the improved die block the nailing machine passes through its usual 65 cycle of operations and the spiked heel is firmly and correctly attached.

In order to accomplish this, provision is made for seating the tread face of the sport shoe heel, regardless of its projecting spikes, 80 flush against the perforated central position of the die block through which the nail drivers 18 operate. As shown best by Fig. 5 there are, in the present instance, a gang of twelve nail drivers for driving an equal number of heel attaching nails 20 through twelve parallel die block nail passages 22 so grouped as to set the nails in the margin of the heel. To be serviceable the spikes must be located near 85 the edge of the heel. Therefore the top lift of the illustrative sport shoe heel has six spikes 24 set in its margin, the heel attaching nails 20 being driven in the margin also, but between the spikes. This arrangement of 90 nails and spikes is highly important as will presently be understood.

Referring to Fig. 3 it will be seen that the nail passages 22 through the die block form a figure of heel lift shape but leaving solid 100

portions 26 of the metal die block between each pair of passages. Obviously if a spiked heel, for example as illustrated in Fig. 4, is held under a die block having merely the usual nail passages the spikes will engage the solid portions 26 and the heel will be held spaced from the plane of emergence of the gang of nail drivers 18 by a distance equal to the height of the spikes 24. Skilled heel attaching machine operators will recognize that such a position of the heel is generally fatal to its accurate attachment to the shoe.

In order to overcome the condition just described each solid die block portion 26 to be engaged by a spike 24 is recessed as at 28 (Figs. 1 and 3), in a definite position relative to the adjoining nail passages 22. The recesses are proportioned to receive the heel spikes which, without undue pressure, may be pushed home, i. e., until the heel stock is in complete engagement with the die block. A sport shoe heel may thus be attached as surely and as accurately as a heel for a walking shoe. In addition to the important advantage just described the relief or recessing of the die block at the points 28 provides, in conjunction with the spikes, guides or gages to enable an operator correctly to locate a heel on the die block relative to the grouping of the gang of nail drivers 18 without the use of separate heel gages. Thus, when the sport shoe heel is placed beneath the die block and its spikes 24 are inserted in the similar spaced recesses 28 it is not only so located as to insure accurate nail driving but the driven nails are definitely spaced between the spikes as fine shoemaking requires.

It will be understood from the foregoing description that the usefulness of the invention is not limited to any particular heel attaching machine, nor to attaching a spiked heel to any particular kind of shoe. Furthermore, in the description and claims the descriptive term "heel" is used in an inclusive sense to denote a top-lift, a rubber heel or a heel built up of two or more lifts or sections that may combine rubber with leather or other heel stock material.

The nature and scope of the invention having been indicated and its preferred embodiment having been specifically described, what is claimed as new, is:—

1. Spiked heel attaching apparatus comprising a shoe support, a gang of nail drivers, and a die block situated between the shoe support and the nail drivers, having nail passages to guide said drivers, said die block having provision for receiving and housing the spikes on a heel to be attached whereby the heel stock lies flush against said die block.

2. Spiked heel attaching apparatus comprising a shoe support, a gang of nail drivers, and a die block situated between the shoe support and the nail drivers, having nail pas-

sages to guide said drivers, said nail driver gang and nail passages being grouped to drive the nails in the margin of the heel, and said die block having a plurality of recesses in its heel engaging face located beside said passages to house the spikes on a heel placed against said die block for attachment to a shoe.

3. Apparatus for attaching sport shoe heels having a series of spikes in the margin of the tread face thereof including a die block having a group of nail passages of heel lift shape in outline to receive a gang of drivers for inserting attaching nails in the margin of the heel, said die block having a series of recesses in its heel engaging face to receive said marginal spikes when a heel is placed against said die block, said recesses being of heel lift shape in outline and each recess being located in the die block material between two of said nail passages.

4. In a heel nailing machine for attaching spiked heels, a die block provided at its heel engaging face with a group of nail passages of heel lift shape in outline for directing nails through the margin of a heel, and a plurality of heel spike receiving recesses formed alternatively with said nail passages in the solid material of the die block between neighboring nail passages as they are grouped to form said heel lift shape.

In testimony whereof I affix my signature.
